UNITED STATES PATENT OFFICE.

JOHN CRAIG AND FRED I. PEASE, OF ERIE, PENNSYLVANIA; SAID PEASE
ASSIGNOR TO SAID CRAIG.

RAILROAD-CROSSING-GATE MECHANISM.

SPECIFICATION forming part of Letters Patent No. 793,029, dated June 20, 1905.

Application filed March 2, 1905. Serial No. 248,084.

To all whom it may concern:

Be it known that we, JOHN CRAIG and FRED I. PEASE, citizens of the United States, residing at Erie, in the county of Erie and State 5 of Pennsylvania, have jointly invented certain new and useful Improvements in Railroad-Crossing-Gate Mechanism; and we do hereby declare the following to be a full, clear, and exact description of the invention, such as will 10 enable others skilled in the art to which it appertains to make and use the same, reference being had to the accompanying drawings, and to the characters of reference marked thereon, forming part of this specification.

15 This invention relates to railroad-crossing gates, and has for its object the construction and arrangement of a crossing-gate mechanism so that the wheels of a train approaching a crossing from either direction will engage 20 and operate mechanism to automatically close the gates before the train reaches the crossing and after the rear of the train has passed the crossing engage and operate mechanism to automatically open the gates, so that from which- 25 ever direction the train comes the crossing-gates will be automatically closed thereby and will remain closed until the rear of the train has passed the crossing and will then be automatically opened thereby.

30 The features of this invention are herein-after fully set forth and described, and illustrated in the accompanying drawings, in which—

Figure 1 is a side view in elevation of a section of a railroad track and crossing with mechanism embodying this invention. Fig. 2 is a top or plan view of the same. Fig. 3 is an enlarged central section of the same in elevation. Fig. 4 is a detail view, partially in elevation 35 and partially in section, on the line xx in Fig. 3. Fig. 5 is an enlarged top or plan view of a portion of the mechanism. Fig. 6 is an enlarged end view of a portion of the mechanism.

40 In the drawings illustrating this invention, A is a railroad-track, and C represents crossing-gates of ordinary construction. On the outside of one of the rails a of the track A we mount longitudinal bars B B at the right and

left hand sides of a railroad-crossing in such 50 manner that they will move vertically up and down, they being supported on vertical links D D, connected with arms d d of bell-crank levers D', so that the movement of the bars B up and down actuates the bell-crank levers D', 55 as and for the purpose hereinafter set forth.

The ends b of the bars B incline somewhat upward from a point at or below the surface of the rail a toward the center of the bar, and then the upper edge is practically level until 60 the end b' thereof, so that the tread of a car-wheel will move up the incline of the bars B from the end b and gradually depress the bars B as the car-wheels move over their upper edge. The ends b' of these bars B, it will be 65 observed, are curved outward from the rail a , as is clearly shown in Fig. 2, so that car-wheels approaching the ends b' of the bars B will crowd the bars B back from the rail and will not run upon them and depress them, and 70 to retain the bars B normally in yielding contact with the outside of the rail a we provide springs a' , engaging sliding bars a'' , which engage the bars B. These bars B are located 75 relatively to each side of the railroad-crossing a sufficient distance at each side of the crossing so that there is ample time for the operation of the mechanism to close the crossing-gates C, hereinafter described, after the head of the train strikes the bar B in the direction 80 from which the train is coming. It will also be observed from the foregoing description that the train operates only the bar B on the side of the crossing from which it comes and passes behind the bar B on the opposite side 85 of the crossing without operating it.

At the side of the rail a of the track A between the bars B and the crossing-gates C, at the right and left hand sides thereof, are mounted bars E E in the same manner as the 90 bars B B, hereinbefore described, are mounted and are supported on vertical links F F, connected with arms f f of bell-crank levers F', so that the movement of the bars E up and down actuates the bell-crank levers F', as and 95 for the purpose hereinafter set forth.

It will be observed from the foregoing description that the train operates the bars E

only after it has crossed the crossing and does not operate the bar B on that side of the crossing as it passes, and, as will be clearly seen by referring to Fig. 1, the train moving in 5 the direction of the arrow 1 will depress the bar B at the right-hand side of the crossing and the bar E at the left-hand side of the crossing, and, vice versa, a train moving in the direction of the arrow 2 will depress the bar B 10 at the left-hand side of the crossing and the bar E at the right-hand side of the crossing. The bars B and E are preferably approximately the length of an ordinary car, so that when one is depressed by the locomotive of a 15 train passing over it the bar will not rise again until the entire train has passed over it.

The crossing-gates C are mounted on posts c and are preferably provided with the usual counterweights c' and are provided with cranks 20 c'', to which links g are connected, leading to cranks g' on transverse shafts G and G', these shafts G and G' being mounted on suitable supports G². On the shaft G there are two loosely-mounted transverse arms H H', (clearly shown 25 in Figs. 4, 5, and 6,) which arms have lugs h h' thereon (see Figs. 3, 4, 5, and 6) adapted to engage studs i i' on a weight I, also mounted loosely on the shaft G, and secured to the shaft G, preferably between the arms 30 of the weight I, there is a cylindrical collar J, provided with peripheral studs j j', with which the weight I automatically engages as it is thrown over from one side of the axis of the shaft G to the other, and by means where- 35 of the shaft G is rotated to the right or left, and to cause the shaft G to rotate gradually under the influence of the weight I, acting thereon, we preferably provide a dash-pot K, connected to the arm k on the shaft G, as is 40 clearly shown in Figs. 1, 3, 4, and 6.

The arms d' d' of the bell-crank levers D' at the right-hand side of the crossing are connected together by a link L, and from thence a connecting-rod L' extends to the upper end 45 of the arm H on the shaft G, and the arms f' f' of the bell-crank levers F' F' at the right-hand side of the crossing are connected together by a link M, and a connecting-rod M' extends therefrom to the lower end of the 50 arm H' on the shaft G.

The arms d' d' of the bell-crank levers D' at the left-hand side of the crossing are connected together by a link L², and from thence a connecting-rod L³ extends to the lower end 55 of the arm H on the shaft G, and the arms f' f' of the bell-crank levers F F at the left-hand side of the crossing are connected together by a link M², and a connecting-rod M³ extends therefrom to the upper end of the 60 arm H' on the shaft G. To the lower end of the arm H and to the upper end of the arm H' retracting-springs N N' are connected to operate against the pull of the rods L' and L³.

The shaft G is provided with an arm O, from 65 which a rod o extends to a like arm O' on the

shaft G', (see Figs. 2 and 3,) whereby the shafts G and G' are caused to rotate toward and away from each other in unison.

In operation a train coming from the direction of the arrow 1 operates to depress the bar B at the right-hand side of the crossing, which operates through the bell-crank levers D' D' connected therewith to rotate the arm H on the shaft G, so as to cause the lug h thereon to engage the stud i on the weight I 75 and raise said weight above and past the center of the shaft G, when the weight I strikes the stud j on the collar J and operates to rotate the shaft G under the restraining action of the dash-pot K, so as to slowly rotate it 80 and the shaft G' connected therewith toward each other and lower the gates C, operated by said shafts, to a horizontal position, as illustrated by dotted lines in Fig. 1. The mechanism then remains in this position until the 85 train passes over and depresses the bar E at the left-hand side of the crossing, which operates on the bell-crank levers F' F', connected therewith through the connecting-rod M², to rotate the arm H' on the shaft G, so as to 90 cause the lug h' thereon to engage the stud i' on the weight I and raise said weight above and past the center of the shaft G when the weight I strikes the stud j' on the collar J and operates to rotate the shaft G under the restraining action of the dash-pot K, so as to slowly rotate it and the shaft G' connected therewith away from each other and raise the gates C, operated by said shafts, to a vertical 95 position, as illustrated by Figs. 1 and 3. 100 When a train approaches the crossing from the direction of the arrow 2, the bar B at the left-hand side of the crossing operates the mechanism to lower the gate C, as hereinbefore described, and the bar E at the right-hand side of the crossing to raise them, as hereinbefore described, the operating mechanism at both sides of the crossing being the same both in construction and operation. 105

We have thus described convenient mechanism for embodying our invention, so as to enable others to utilize the same; but we do not confine ourselves to the exact details of the same herein shown and described, as it is obvious that many modifications can be made 110 therein without departing from the spirit of our invention. 115

Therefore what we claim as new, and desire to secure by Letters Patent of the United States, is—

1. The combination in a railway-crossing-gate mechanism, of a gate pivoted to a post at the side of the crossing, a gate-operating shaft connected therewith, a depressible bar at the side of the railroad-track rail at one 120 side of the crossing adapted to be depressed by the wheels of a car approaching the crossing from that direction, mechanism connecting said depressible bar with a loosely-mounted arm on the gate-operating shaft, a swing- 125

ing weight on said shaft adapted to be engaged by said arm and operated to engage and rotate said shaft to automatically lower the gate when said bar is depressed, another 5 depressible bar at the side of said railroad-track rail on the opposite side of the crossing adapted to be depressed by the wheels of a car after it has passed the crossing, mechanism connecting said depressible bar with an 10 other loosely-mounted arm on the gate-operating shaft, and adapted to engage said swinging weight and operate it to rotate said shaft to automatically raise the gate after the train has passed the crossing, substantially as set 15 forth.

2. The combination in a railroad-crossing-gate mechanism, of gates pivoted to posts at each side of the crossing, gate-operating shafts connected with said gates, mechanism connecting 20 said gate-operating shafts so that they will rotate in unison toward and from each other, a depressible bar at the side of the railroad-track rail on each side of the crossing, adapted to be depressed only by the wheels 25 of a car approaching the crossing, mechanism connecting said depressible bars, one with the upper and the other with the lower end of an arm loosely mounted on one of the gate-operating shafts, a swinging weight on said shaft 30 adapted to be engaged by said arm and actuated to engage and rotate said shaft to automatically lower the gates when either of said depressible bars is depressed, two other depressible bars at the side of the railroad-track 35 rail, at opposite sides of and between the crossing and the first-named depressible bars, adapted to be depressed by the wheels of a car after it has passed the crossing, and mechanism connecting these depressible bars one 40 with the upper and the other with the lower end of another loosely-mounted arm on said gate-operating shaft, adapted to engage said swinging weight and operate it to rotate said shaft to automatically raise the gates after 45 the train has passed the crossing, substantially as set forth.

3. The combination in a railroad-crossing-gate mechanism, of a gate pivoted to a post at the side of the crossing, a gate-operating shaft 50 connected therewith, a depressible bar at the side of the railroad-track rail, at one side of the crossing, adapted to be depressed by the wheels of a car approaching the crossing from that direction, bell-crank-lever mechanism 55 yieldingly supporting said bar, a weight swinging loosely on the gate-operating shaft, a collar secured to said shaft, lugs thereon adapted to engage and move said weight so that the shaft will be rotated thereby, a 60 loosely-mounted arm on said shaft adapted to engage said weight and swing it over so that said shaft will be rotated thereby in one direction, and a rod connecting said arm and

said bell-crank levers, substantially as set forth. 65

4. The combination in a railroad-crossing-gate mechanism, of a gate pivoted to a post at the side of the crossing, a gate-operating shaft connected therewith, a depressible bar at the side of the railroad-track rail, at one side of the crossing, adapted to be engaged by the treads of the wheels of a car approaching the crossing from that direction only, a weight swinging loosely on the gate-operating shaft, a collar secured to said shaft, lugs thereon 70 adapted to engage said weight so that the shaft will be rotated thereby, a loosely-mounted arm on said shaft adapted to engage said weight and swing it over in one direction so that it will operate said shaft in one direction, mechanism connecting said depressible bar with said loosely-mounted arm so as to operate it on said shaft, and another depressible bar at the side of the railroad-track rail, on the opposite side of the crossing from the first-named depressible bar, and adapted to be engaged by the treads of the wheels of a car only after it has passed the crossing, another arm on the gate-operating shaft adapted to engage the weight and swing it over in the opposite direction, mechanism connecting said last-named depressible bar with said last-named loosely-mounted arm so as to operate said shaft in the opposite direction from that first-described, and a dash-pot so connected 85 with said shaft as to control the speed of its rotation under the action of said swinging weight, substantially as set forth. 90

5. The combination in a railroad-crossing-gate mechanism, of a gate pivoted to a post at the side of the crossing, a gate-operating shaft connected therewith, a depressible bar at the side of the railroad-track rail, at one side of the crossing, adapted to be depressed by the wheels of a car approaching the crossing from that direction, a weight swinging loosely on the gate-operating shaft, a collar secured to the shaft, lugs thereon adapted to engage and move said weight so that it will be rotated thereby, a loosely-mounted arm on said shaft 100 adapted to engage said weight and swing it over so that it will engage and rotate the shaft, mechanism connecting said arm and said depressible bar, a retracting-spring acting on said arm against the action of the other mechanism acting thereon, and a dash-pot connected with said shaft to control the speed of its rotation under the action of the swinging weight, substantially as set forth. 105

In testimony whereof we affix our signatures 110 in presence of two witnesses.

JOHN CRAIG.
FRED I. PEASE.
